(57) **CLAIM**

The ornamental design for a paint spraying system, as shown and described.

DESCRIPTION

FIG. 1 is a top perspective view of a paint spraying system showing our new design;

FIG. 2 is a bottom perspective view thereof;

FIG. 3 is another top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is an enlarged view of portion 10 in FIG. 1.

The broken lines in the drawings illustrate portions of the paint spraying system which form no part of the claimed design.

1 Claim, 10 Drawing Sheets
